WINDOW SCREEN CONSTRUCTION

Joseph F. Kaletay, Reaville, N. J.

Application July 6, 1935, Serial No. 30,053. Renewed January 16, 1937

12 Claims. (Cl. 156—39)

This invention relates to frames for window screens and particularly to frames adapted to fit the entire window opening and provided with a shade roll type of screen.

5 In addition to being constructed in many different sizes, window frames vary materially in size even where intended to be uniform. Hence, the usual practice was to construct a screen frame to fit the measurements of a particular window frame. The impracticability of such practice is quite apparent. Also, a frame so constructed was fitted with a screen which was fixed and, of necessity, had to be applied outside the window sashes where it was exposed to the deleterious action of the weather. The provision of this type of screen for casement windows has not successfully been accomplished heretofore.

10 The present invention, therefore, seeks to provide a screen frame, adjustable for size within certain limits, and adapted to support and clamp a shade roll type of screen in any adjusted position of said screen.

15 The invention further seeks to provide a screen frame which may be universally applied to either sliding sash windows or casement windows, by applying said frame on the room side of the window frame, access to the windows being had through the frame opening.

20 The invention also contemplates the provision of improved means for varying the size of a screen frame as contemplated in this invention.

25 Another contemplated feature resides in the provision of simple means for effectively clamping said screen in any adjusted position in said frame.

30 The foregoing features which are broadly stated and many others, more specific, will be more clearly apparent from the following detailed specification based on the accompanying drawings which illustrate a preferred embodiment of the invention.

35 In the drawings:

40 Fig. 1 is a front view of a screen frame constructed in accordance with this invention.

45 Fig. 2 is an enlarged vertical sectional view as taken along the line 2—2 of Figure 1.

50 Fig. 3 is an enlarged front view of a fragment of a lower corner portion of the frame.

55 Fig. 4 is a bottom view thereof.

Fig. 5 is an enlarged sectional view as taken along the line 5—5 of Figure 3.

Fig. 6 is a similar view showing the screen size adjusting mechanism in released position.

Fig. 7 is an enlarged detail sectional view as taken along the line 7—7 of Figure 3.

Fig. 8 is a similar view in the screen clamping position.

Fig. 9 is a sectional detail view as taken along the line 9—9 of Figure 7.

Fig. 10 is a cross-sectional view to an enlarged scale, of the screen edge clamping means as taken along the line 10—10 of Figure 3.

Fig. 11 is a similar view showing the screen edge clamping position of said clamping means.

Fig. 12 is a view similar to Figure 11 of an alternate form of screen edge clamping means.

Fig. 13 is a front view of a non-adjustable frame constructed in accordance with this invention.

Referring to the drawings in greater detail, the frame is preferably formed of four L-shaped members 15, 16, 17 and 18, the horizontal leg 19 of the member 15 being telescoped within the leg 20 of the member 16, the horizontal leg 21 of the member 18 being telescoped within the leg 22 of the member 17, and the vertical legs or stiles 23 and 24 of the members 17 and 18 respectively, being telescoped within the stiles 25 and 26 of the respective members 16 and 15.

As can be noted from this structure, the frame may be varied in the size of both the length and width dimension to a degree commensurate with the amount of telescopic engagement of the various leg portions of the members comprising the frame.

The elements or members of the frame are each preferably formed with a U-shaped section having the ends of the U turned inwardly as shown in Figures 7 and 10. In this manner there is provided guideways 27 for the side edges of a screen 28 on a spring roll 29 mounted in a casing 30 carried by the element 17 of the frame. The bottom edge of the screen is preferably provided with a stiffening member 31 provided with a lip or flange 32.

At each point of telescopic engagement between cooperating portions of the frame elements there is preferably provided means for locking said portions in adjusted relation. Since all of these means are substantially alike, only one, will be described, the one shown at the lower left hand corner of the frame being chosen.

The outer leg 20 is preferably provided with pairs of opposed guides 33 in which a casing 34 is arranged to slide. The top and bottom walls of this casing are each provided with a slot 34a in which is guided a cross pin 35 secured to a

dog 36 guided in a slot 37 in the casing 34. The dog 36 is formed with a lug 38 normally projecting through an opening 39 in the leg 29 and engageable against one of the edges 40 of a plurality of slots 41 in the telescoping leg 19. The dog 36 is, also, preferably formed with a projection 42 for the purpose of releasing said lug 38 from engagement with an edge 40.

Between the edge 43 of the dog 36 and the end wall 44 of the casing there is preferably arranged a coil spring 45 and, if desired, said spring may be provided with a tubular cap 46 as shown.

At the open end of the casing 34 and pivoted at 47 thereon, there is provided link means 48 connected to an intermediate portion at 49 to a toggle lever 50 mounted on the pivot pin 51 on a fixed lug 52 on the leg 20.

In association with the end wall 44 of the casing 34, there may be provided a lug 53 on the portion 20.

When a screen frame is to be applied to a window frame, the toggle lever 50 is lifted as shown in Figure 6 permitting the housing to abut the lug 53 and thereby raising the dog 36 so its lug 38 assumes a position upon the outer surface of the member 20. The screen frame elements are then adjusted in proper relation, i. e. against the jambs, sill, and top rail of the window frame.

The toggle lever 50 is then rocked down to the position shown in Figure 5, exerting a pull on the casing 34 and, through the medium of the spring 45, forcing the dog 36 so the lug 38 thereon engages that edge 40 of the slots 41 which is in its path. Since the pivot 51 is out of line with the pivots 47 and 49 the toggle lever 50 will retain its position until released. Also, since the slot 39 is long enough to include one of the slots 41 and a bridge portion therebetween, quite fine adjustment of the screen frame can be obtained.

The spring 45 forces the dog 36 and, therefore, the frame element 15 in one direction, and the casing 34 and, therefore, the frame element 16 in the opposite direction. This insures positive positioning of the screen frame within the window frame.

The screen 28 may be pulled down to any selected intermediate position in the frame or completely down and clamped in that position. A preferred means for accomplishing this, here disclosed, comprises a handle 54 pivoted at 55 to the element 20 of the frame, and through links 56 and 57 and slide rods 58 and 59, is adapted to rock the shafts 60 and 61 through the medium of the lever 62 and 63.

The shafts 60 and 61 are mounted in bearings 64 and extend upwardly to a point beyond the middle of the frame. Upon these shafts are fixed a plurality of clamps 65 which through openings 66 in the frame are adapted to impinge on the edges of the screen as shown in Figure 11. In order not to mutilate the screen the clamping portions of the said clamps may be lined with a material such as leather or felt as shown at 67.

If desired, as shown in Figure 12, the clamps 65 may be engaged against one of the inwardly bent portions 68 of the elements of the screen frame which in turn is urged to impinge the screen in clamping relation.

To permit the above described adjustment of the screen frame, the slide bar 58 may be made adjustable, as shown at 69, and for the purpose of effectively gripping the bottom stiffening member 34 when the screen is completely pulled down in the frame, the leg 20 is slotted as at 70 and

the slide bars 58 and 59 are provided with offset portions 71 which force the portion 20a of the leg 20 into engagement with said stiffening member through the medium of the loops 72 as best seen in Figure 9. The released and gripped conditions of said stiffening member are clearly shown in Figures 7 and 8 respectively.

It is, of course, understood that the screen clamping means may be employed on a non-adjustable frame, as shown in Figure 13 and, similarly, the adjusting means here disclosed may be used on screens having other screen clamping means.

As can be understood from the foregoing, a screen frame has been provided which may be expeditiously applied to either a sliding sash or casement window and is adapted, by the mere manipulation of a single handle, to clamp a screen therein in any required position. It is also apparent that immaterial changes in construction and in the arrangement and sizes of the parts may well be made without departing from the true spirit and scope of the invention as herein-after claimed.

I claim:

1. In a screen frame comprising a plurality of telescoping elements, means for locking associated elements in adjusted relation in a window frame, said means comprising a member slidably carried by one element, a member supported thereby and engaging the other element, spring means therebetween, and toggle means for compressing said spring means.

2. In a screen frame comprising a plurality of telescoping elements, means for locking associated elements in adjusted relation in a window frame, said means comprising a member slidably carried by one element, a member supported thereby and engaging the other element, spring means housed in the slidable member and engaged against the supported member for forcing said members in opposite directions, and toggle means for compressing said spring means.

3. In a screen frame comprising a plurality of telescoping elements, means for locking associated elements in adjusted relation in a window frame, said means comprising a member slidably carried by one element, a member supported thereby and engaging the other element, spring means housed in the slidable member and engaged against the supported member for forcing said members in opposite directions, link means on the slidable member, and a toggle lever pivoted to the element supporting said slidable member and to said link means for compressing said spring means.

4. In combination, an adjustable frame, means for locking said frame in adjusted position in a window opening, a roll screen having its lateral edges guided in the vertical portions of said frame, and means for locking said screen in any adjusted position in said frame.

5. In combination, an adjustable frame, means for locking said frame in adjusted position in a window opening, a roll screen having its lateral edges guided in the vertical portions of said frame, and means for clamping the lateral edges of said screen, said means operating through openings in the frame.

6. In combination, an adjustable frame, means for locking said frame in adjusted position in a window opening, a roll screen having its lateral edges guided in the vertical portions of said frame, and means for clamping the lateral edges of said screen, said means comprising a handle,

- a plurality of clamp members and means connecting said handle and clamp members.
7. In a screen frame having a roll screen, means for clamping said screen in any adjusted position in the frame, said means comprising a single handle, clamp members engageable with the lateral edges of the screen, and means connecting said handle and clamp members.
8. In a screen frame having a roll screen, means for clamping said screen in any adjusted position in the frame, said means comprising a single handle, a rock shaft mounted on the stiles of the frame, said stiles having a plurality of openings, linkage connecting the handle with each rockshaft, and clamp members on said rockshafts operating through the openings in said frame stiles for engaging the lateral edges of said screen.
9. In a screen frame having a roll screen, means for clamping said screen in its lowermost position in said frame, said frame having a slotted portion, said means comprising a single handle, and means connected to said handle for urging the slotted portion of said frame laterally into engagement with the bottom edge of said screen.
10. In a screen frame having a roll screen, means for clamping said screen in its lowermost position in said frame, said means comprising

a resilient portion of the screen frame, a single handle, means for urging said resilient portion laterally against the bottom of said screen, and means connecting said handle and said urging means.

11. In a screen frame having a roll screen, a slotted resilient portion in the bottom rail of said frame, means for clamping said screen in its lowermost position in the frame, said means comprising means for urging said resilient portion laterally against the bottom of said screen, clamp members engageable with the lateral edges of the screen, a single handle, and means connecting said handle, said urging means and said clamp members.

12. In a screen frame having a roll screen, a slotted resilient portion in the bottom rail of said frame, means for clamping said screen in its lowermost position in the frame, said means comprising a rock shaft mounted on each stile of said frame, said stiles having a plurality of openings, clamp members on said rock shafts operating through the openings in said frame stiles for engaging the lateral edges of said screen, a single handle, linkage connecting the handle with each rock shaft, and means on the linkage for urging said resilient portion laterally against the bottom of said screen.

JOSEPH F. KALETAY.
